By Drake & Co. Atty.

UNITED STATES PATENT OFFICE.

JAMES BOWERS, OF NEWARK, NEW JERSEY.

DESIGN FOR A CORSET.

SPECIFICATION forming part of Design No. 14,466, dated December 11, 1883.

Application filed August 29, 1883. Term of patent 3½ years.

To all whom it may concern:

Be it known that I, JAMES BOWERS, a citizen of the United States, residing at Newark, in the county of Essex and State of New Jersey, have invented and produced a new and original Design for Corsets; and I do hereby declare the following to be a full, clear, and exact description of the invention, such as will enable others skilled in the art to which it applies to make and use the same, reference being had to the accompanying drawings, and to letters of reference marked thereon, which form a part of this specification.

In the drawings, Figure 1 represents one of the breast-gores of a corset, this being the portion to which the design relates, and Fig. 2 is a section through line *x*, to show the corrugations therein. Said figures are deemed sufficient to illustrate the design.

The leading feature of my design is a corset

having the surface of the breast portion thereof ridged or corrugated, substantially as shown, and as will be more particularly described. In the gores at the sides of the middle portion, *e*, of the breast portions of a corset, the surface of said breast portion is ridged at the top, as at *a a*, with vertical or approximately vertical ridges, below which said breast is horizontally or approximately horizontally ridged or corrugated.

25

What I claim is—

The design for a corset breast-gore, substantially as shown and described.

In testimony that I claim the foregoing I have hereunto set my hand this 28th day of 35 August, 1883.

JAMES BOWERS.

Witnesses:

OLIVER DRAKE,
F. F. CAMPBELL.
